UNITED STATES PATENT OFFICE

2,098,965

CLOCK

Henry C. James, Jr., Oakland, Calif., assignor to
National Products, Inc., a corporation of Cal-
ifornia

Application February 24, 1936, Serial No. 65,453

5 Claims. (Cl. 200—38)

This invention relates to clocks and especially to that type known as alarm, reminder, program and electric appliance clocks, the present application being a continuation in part of my copending application 5 entitled "Clocks" filed November 7, 1933, Serial Number 697,032.

The object of the present invention is generally to improve and simplify the construction and operation of clocks of the character described; to provide a single pair of contacts through which an electric circuit may be closed at any hour or minute indicated on the clock dial; to provide a carrier adapted to be rotated on the clock mechanism one complete revolution in unison with the hour, minute or second hand on the clock, said carrier forming a support for a switch contact having a pair of contacts and said contacts being insulated from said clock mechanism and said switch mechanism being insulated from the clock and its frame; to provide means for connecting said switch with a suitable source of electric current supply; to provide adjustable actuators in the path of travel of the carrier and switch for automatically opening and closing a circuit through the switch contacts at selected time intervals; and, further, to provide a friction means for retaining the actuators in position when adjusted.

The invention is shown by way of illustration in the accompanying drawings, in which—

30 Fig. 1 is a front view of the clock;

Fig. 2 is an enlarged rear view of a portion of the clock showing the collector rings, the switch, the contacts carried thereby, the cam and the actuators;

35 Fig. 3 is an enlarged front view of a portion of the clock dial and the alarm dial;

Fig. 4 is a rear view partially broken away and partially in section;

Fig. 5 is a central, vertical cross section;

40 Figs. 6 and 7 show modified forms of cams;

Fig. 8 is a side elevation of one of the actuators; and

Fig. 9 is an end view thereof.

Referring to the drawings in detail, and particularly Figs. 1 and 5, A indicates a clock housing or casing of suitable design in which is mounted the main frame of a clock. The frame consists of three plates, indicated at 2, 3 and 4, which are spaced apart by posts 5 and 6. Secured to the 50 rear face of the plate 2 is a synchronous electric alternating current motor 7 and driven thereby is the usual gear train 8, which drives the arbors 9, 10 and 11, carrying the second hand 12, the minute hand 13, and the hour hand 14. Secured to the hour hand arbor 11 and insulated

therefrom is a carrier 15 on which is secured a pair of collector rings 16 and 17, see Figs. 3 and 4, and delivering current to said rings are brushes 18 and 19 which are connected to a suitable source of electric alternating current supply through 5 wires 18a and 19a. These wires may be connected direct with 110 volt power circuit, or the like, or the current may be stepped down through a transformer 20, and a buzzer or other signal or alarm device may be placed in the circuit as indicated 10 at 21.

Also secured to the carrier are a pair of arms 16a and 17a which are counterweighted as shown. Arm 16a is connected to the collector ring 16 and arm 17a to the collector ring 17. The arms are 15 insulated from each other and the arm 17a carries a flexible switch arm 22 having a contact 23 and also carries a cam 24 on its outer end. Arm 16a carries a contact 25 through which the alarm or signal circuit is closed when the switch 20 arm is depressed.

In order that the circuit through the contacts 23 and 25 may be closed to sound an alarm, etc., at selected time intervals means are provided for rotating the carrier which supports the switch, said means being in this instance the hour hand arbor 11 to which the carrier is secured and means must be placed in the path of travel of the cam 24 to engage and depress it so as to bring the contacts 23 and 25 into engagement with each other. 30 The means employed are the crank pins generally indicated at C, see Figs. 5, 8 and 9. There are forty-eight of them and they are journaled between the frame plates 3 and 4. The journal section of each pin is indicated at 27 and 28, a 35 crank portion at 29 and there is also a handle extension 30 for rotating the cranks. A graduated dial B, hereinafter to be referred to as the alarm dial, is secured to the outer face of the clock housing and surrounds the clock dial D. 40 The dial B has a plurality of arcuate slots formed therein through which the handle ends 30 of the cranks extend a sufficient distance to permit them to be grasped whenever a crank is to be adjusted. These cranks will hereinafter be referred to as actuators. They are arranged in a circle 45 concentric to the path of travel of the cam 24 and normally assume a position out of contact therewith, but by grasping one or another of the handle sections 30 and swinging it toward the inner ends 50 of the arcuate slots the crank or cranks connected therewith will similarly swing inwardly as shown at 34 in Fig. 2. In this position the cam 24 will engage the crank or cranks and as such will be 55

depressed sufficiently to cause the contacts 23 and 25 to engage and close the alarm circuit.

When engagement is made between the cam 24 and any of the cranks swung into the path of travel of the cam, there would be a tendency for the crank or cranks to swing out of the way and if that were the case no alarm or signal would be given as the switch arm would not be depressed; hence means must be provided for securing 10 the cranks against rotation when engaged by the cam.

This is accomplished in the present instance by winding a comparatively stiff flat leaf spring 40 between the inner projected ends 28 of the crank pins, as clearly shown in Figs. 4 and 5. This flat spring exerts such a friction on the crank pins that when engaged by the cam 24 there is no chance of displacing or changing their position for they are thus frictionally held and swing 20 inwardly into the path of travel of the cam.

When the crank handles 30 are moved or swung to the outer ends of the arcuate slots, as shown at 30 in Fig. 3, the cranks 29 will assume the position indicated at 29^a in Fig. 2 and cam 24 will 25 travel free or out of engagement. Conversely, if the crank handle is swung toward the inner end of a slot, as shown at 30^a in Fig. 3, the corresponding crank will assume the position shown at 34 in Fig. 2. In that case cam 24 will engage 30 the crank and depress the switch arm 22 sufficiently to close a circuit through the contacts 23 and 25.

The dial containing the arcuate slots and the protruding handles 30 is graduated into hours 35 and fifteen minute intervals, said graduations being arranged in a circle concentric to the clock dial and being indicated at 45, see Fig. 1. Graduations are also arranged lengthwise of the arcuate slots, as shown at 46. These graduations indicate five minute intervals but, nevertheless, 40 permit setting of the handles at any point between the ends of the arcuate slots, hence making it possible to accurately set an alarm for any five minute period but by setting the handles at 45 points intermediate the five minute graduations it is possible to set an alarm for any minute indicated on the clock dial.

Suppose a series of alarms, signals, or electric circuits are desired at the following times: 12:05; 50 12:15; 12:40; 12:55; 3:00; 3:45; 5:00; 11:00. If that is the case the proper handles 30 will be swung to the different settings on the alarm dial, and if the clock is being used as a reminder clock at the time an alarm is given the alarm or signal 55 is stopped by returning the particular handle to the outer end of the arcuate slot so as to break the circuit as soon after the alarm has been given as possible. If the clock is being used as a program or radio clock, the handles 30 are not disturbed as each contact is made. In the case of a radio clock the handles should be returned to off position on the outer ends of the slots at the close 60 of the day. In the case of a program the handles should be left in their set positions until such time as the daily program is to be changed.

Where 110 volts, or a similar current is used, the cam 24 is made of fiber or a similar non-conducting material so that there will be no chance of a person operating the clock getting an electric shock. This is true where both types of contact shown in Figs. 2 and 6 are employed. Where a contact such as shown in Fig. 7 is used, the current is reduced to a very low voltage through a 70 transformer, such as shown at 20, so that any 75

current that might pass through the handles 30 will not be felt by the operator.

The mechanism here illustrated actuates a self contained switch or circuit mechanism and breaker which is carried either by the hour or minute hand arbor or by the hands themselves. The switch and the collector rings are entirely insulated from the rest of the clock mechanism and as such permit the use of a current directly from a 110 volt power circuit, or the like, without any danger to a person operating the clock. The cam 24 which actuates the switch will have different shapes so that the clock may be adapted to various uses.

As an example one style of cam will operate as 15 an alarm or reminder clock, as shown in Figs. 2 and 4. The shape of the cam is such that if the clock hands are turned backwards while any of the actuating cranks 29 are swung downwardly the cam will pass over them without doing any 20 damage to the flexible arm 22 of the switch. In other words the hands can be turned either backward or forward without damage to the mechanism. The cam shown in Fig. 6 closes the circuit and holds it closed for just fifteen minutes 25 and then it breaks contact quickly. This type of cam is employed for turning on the radio, or any other ordinary electric appliance. If it is desired to hold the circuit closed for half an hour or more it can be accomplished by swinging two or more 30 consecutive actuating cranks 29 inwardly into engagement with the cam. Each cam will hold the circuit for fifteen minutes.

Another type of contact, such as shown in Fig. 7, is made by simply bending up the end of the 35 spring arm 22. This type is intended for operating the clock as a program clock for small schools, factories, stores, etc., where the same program or alarm signals are continued day in and day out. For this type of signal the contact 40 is kept closed for a very short period of time.

An alarm mechanism constructed as here shown is absolutely dependable, first because silver contacts are employed at the points indicated at 23 and 25. No matter how much oxide forms 45 on these points they are just as good a conductor of electricity as when new. Secondly, when the cam 24 comes into contact with one of the actuators or cranks 29 it first has a tendency to take up all the slack or lost motion which is common 50 to all clocks so that at the actual time of electric contact everything is under tension and a good solid contact is made between the points 23 and 25.

The actuators or cranks 29 employed allow 55 alarms or signals to be set up in advance at any time desired. The number of time intervals at which a signal may be set is not limited to the number of cranks or actuators employed. As an example, in certain constructions of this character using forty-eight actuators, it is only possible to set the alarms at fifteen minute periods. With the same number of actuators, I can provide an alarm circuit at any minute indicated on the clock dial, and while these and other features 60 have been more or less specifically described and illustrated, I wish it understood that various changes may be resorted to within the scope of the appended claims. Similarly, that the materials and finish of the several parts employed may 65 be such as the manufacturer may decide, or varying conditions or uses may demand.

Having thus described my invention, what I claim and desire to secure by Letters Patent is:—

1. In combination with a clock mechanism, a 75
